UNITED STATES PATENT OFFICE

136,882

DESIGN FOR A COMBINED VALVE AND OPERATING ATTACHMENT

Walter T. Caldwell, Enid, Okla., assignor to The
George E. Failing Supply Company, Enid, Okla.,
a corporation of Oklahoma

Application October 16, 1943, Serial No. 111,400

Term of patent 14 years

To all whom it may concern:

Be it known that I, Walter T. Caldwell, a citizen of the United States, residing at Enid, in the county of Garfield and State of Oklahoma, have invented a new, original, and ornamental Design for a Combined Valve and Operating Attachment, of which the following is a specification, reference being had to the accompanying drawings, forming a part thereof.

Fig. 1 is a perspective view of a combined

valve and operating attachment, showing my new design;

Fig. 2 is a top plan view;

Fig. 3 is an end elevational view; and

Fig. 4 is a side elevational view thereof.

I claim:

The ornamental design for a combined valve and operating attachment, as shown.

WALTER T. CALDWELL.
